UNITED STATES PATENT OFFICE.

WILLIAM H. TICHBORNE, OF WHEELING, WEST VIRGINIA.

DRINKING-CUP.

1,117,109.

Specification of Letters Patent.

Patented Nov. 10, 1914.

Application filed September 12, 1913. Serial No. 789,480.

To all whom it may concern:

Be it known that I, WILLIAM H. TICHBORNE, a citizen of the United States, residing at Wheeling, in the county of Ohio and State of West Virginia, have invented new and useful Improvements in Drinking-Cups, of which the following is a specification.

An object of the invention is to provide a collapsible drinking cup.

10 The invention embodies, among other features, the provision of a drinking cup which can be collapsed so as to readily fit into the pocket and which is preferably made of a material permitting of the drinking cup being readily cleaned so as to present a neat and sanitary appearance and which, furthermore, can be used many times and will not easily wear out or become broken.

20 A still further embodiment of the invention is the provision of a drinking cup which can be cheaply manufactured and which embodies few and simple parts that can be readily assembled for the purpose of obtaining the desired result.

25 In the further disclosure of the invention reference is to be had to the accompanying drawings, constituting a part of this specification, in which similar characters of reference denote corresponding parts in all the 30 views, and in which:

Figure 1 is a perspective view of the drinking cup showing the same in open position; Fig. 2 is a plan view of the drinking cup showing the same in collapsed position; 35 Fig. 3 is a transverse vertical sectional view of the structure as disclosed in Fig. 1; Fig. 4 is a fragmentary vertical sectional view taken on the line 4—4 in Fig. 2; and Fig. 5 is a vertical sectional view taken on the line 40 5—5 in Fig. 2.

Referring more particularly to the views, I provide a plurality of cup forming members 10 and 11, the cup forming member 11 being slightly larger than the cup forming 45 member 10, and the said cup forming members being preferably made of a spring-like flexible material such as celluloid or the like. The cup forming member 10 is somewhat egg shaped in contour and at its ends 50 12 carries connecting members 13 in the form of rivets or the like, and which have their stems 14 projecting through slots 15 formed in the ends 16 of the cup forming member 11. When the connecting members 55 13 are in the form of rivets as mentioned, the stem 14 of each member includes an in-

tegral head 17 abutting against a face of the cup forming member 10 and the free end of the stem has applied thereto an auxiliary head 18 abutting against a face of the cup forming member 11, as shown. 60

Now referring to the views it will be apparent that when the drinking cup is in the position shown in Fig. 2, the cup forming members will lie flat against each other, with the stems of the connecting members lying at the inner ends of the slots 15. Now in order to arrange the cup forming members to provide a receptacle 19 as shown in Fig. 1, the cup forming member 11 is preferably 70 held in one hand at the point 20 and a pressure is exerted against the cup forming member 10 at the point 21, thus causing the inner edge of the cup forming member 10 to slide on the inner face of the cup forming 75 member 11 and form the receptacle 19, the stems 14 of the connecting members 13 being adapted to slide in the slots 15 so that when the cup forming members are arranged in receptacle-forming position the 80 stems of the connecting members will lie in the outer ends of the slots and the inner edge of the cup forming member 10 will abut against the inner face of the cup forming member 11, thus forming a water-tight 85 joint. By simply pressing upwardly on the cup forming member 10 adjacent its inner edge, the cup forming members, owing to their collapsible nature, will readily assume the collapsed position shown in Fig. 2 so 90 that the drinking cup can be easily placed in the pocket and will take up very little room.

As mentioned heretofore, I preferably form the cup forming members of celluloid, 95 although it will be understood that any other suitable flexible and fluid-proof material can be used.

I do not contemplate my drinking cup for use in the manner of the ordinary china 100 drinking cups used in households, but more as an article which can be conveniently carried by tourists, pedestrians, or on trains or other vehicles and in which cases it is desirable to have a drinking cup which will 105 take up very little room; which will be clean and sanitary and which can be cheaply manufactured to present a convenient, collapsible article.

Having thus described my invention, I 110 claim:

1. In a drinking cup, the combination

with two flat collapsible cup-forming members, one of which is provided with a plurality of opposed slots and larger than the other cup-forming member, of connecting members carried by the other cup-forming member and having portions thereof slideable in the slots to connect the cup-forming members at their ends whereby they can be relatively flexed to provide a substantially 10 conically shaped receptacle.

2. In a drinking cup, the combination with a plurality of flat flexible cup-forming members, one of which is provided with a plurality of slots at its ends and larger than the other cup-forming member, of means carried by the other cup-forming member and operating in the slots of the first mentioned cup-forming member and relatively connecting the cup-forming members, 15 whereby they can be relatively positioned to form a receptacle, with an edge of the smaller cup-forming member lying within

and abutting against the inner face of the larger cup-forming member.

3. As a new article of manufacture, a 25 drinking cup comprising two flexible cup-forming members, one of which is larger than the other and provided with a plurality of similar slots, and members carried by the smaller cup-forming member and slideable in 30 the slots of the larger cup-forming member whereby the cup-forming members can be relatively positioned so that an edge of the smaller cup-forming member will lie within and abut against the inner face of the 35 larger cup-forming member to form a conical receptacle.

In testimony whereof I affix my signature in presence of two witnesses.

WILLIAM H. TICHBORNE.
